CLAIM

The ornamental design for a vehicle light, as shown and described.

DESCRIPTION

FIG. 1 is a isometric view of a vehicle light designed according to the present invention with the broken line showing for illustrative purposes only and forming no part of the claimed design;

FIG. 2 is a top plan view of the vehicle light shown in FIG. 1;

FIG. 3 is a front plan view of the vehicle light shown in FIG. 1;

FIG. 4 is a side plan view of the vehicle light disclosed in FIG. 1, with the opposite side view being a mirror image of FIG. 4;

FIG. 5 is a bottom plan view of the vehicle light shown in FIG. 1;

FIG. 6 is a rear plan view of the vehicle light shown in FIG. 1; and,

FIG. 7 is a bottom plan view of an alternative embodiment shown in FIG. 1 having a clear transparent insert placed in the bottom panel of the vehicle light.
